Application May 12, 1942, Serial No. 442,688

5 Claims. (Cl. 89—41)

1

This invention relates to remote control for power-operated devices and is herein shown as embodied in an arrangement in which it is desired to have the movements of the device correspond to the movements of a control member. The invention will be herein described in its application to the training of a gun but it will be understood that, broadly, it is equally adapted to remote control of other devices, such as moving tools or the like in shoe machinery.

An object of the invention is to provide an improved remote control mechanism for a device capable of movement in a plurality of paths, as in planes normal to one another. The direction, extent, and speed of movement of the device to be controlled will correspond exactly or correspond in a predetermined ratio with the direction, extent, and speed of movement of the operator-controlled member, to the end that an operator who has been accustomed manually to control the device in its various movements will readily effect a corresponding control by similar movements of a remotely located control member.

Guns mounted upon airplanes are usually supported for substantially universal movement within a limited range as, for example, by pivotally supporting the guns for tilting movement about one axis to control the elevation and for swinging movement about an axis normal to the first to control the deflection or azimuth. The space in which said guns are mounted is cramped and, usually, adequate armor protection for the operator cannot be provided adjacent to the guns. It is well understood also that the force required to hold such a gun against the pressure of the air stream is very considerable and that it thus interferes with the speed with which such gun may be trained and the accuracy with which it may be held in the desired position.

A more specific object of the invention is to provide a remotely located control handle mounted for substantially universal movement in a protected portion of the airplane and to connect that control handle to a similarly mounted gun by power-operated apparatus including a follow-up mechanism connected directly to the movable device, such as the gun, to the end that the direction, speed and extent of movement of the device shall correspond to the direction, speed and extent of movement of the control member.

In the case of machine guns, for example, these are usually pivotally mounted for movement about axes located in planes which are normal to one another and are trained by handles secured to the rear end of the gun. To enable a trained gunner to learn quickly to operate the gun by remote control, provision has been made, according to our invention, of a control handle mounted for substantially universal movement and arranged continuously to control the movements of

2

the gun by movements of the handle which correspond exactly in direction or angularity to those of the gun and correspond in a predetermined ratio with the speed and extent of movement of the gun. Furthermore, to avoid the necessity for the operator to return the control handle to a zero or neutral position after every movement of the gun, follow-up mechanisms have been provided so that the stopping of the handle is effective immediately to stop the movement of the gun. Furthermore, if an operator moves the handle quickly, the gun moves quickly with a corresponding speed. The follow-up mechanism positioned between the control member and the power-operated mechanism is arranged to operate without overthrow or inaccuracy by directly connecting the follow-up to the movable part of the power-operated mechanism and hence to the gun itself. Another part of the follow-up mechanism is connected directly to the control handle and the connections are arranged to have opposite effects, to the end that the gun is brought to a stop when the operator-controlled member is stopped.

In the illustrated apparatus, fluid-pressure motors are provided for causing the movements of the gun, and these are controlled by balanced valves, so that, once the gun is positioned, it is held automatically in that position without effort on the part of the operator. The valves have movable members which are directly operated by follow-up levers having dual fulcrums one of which is directly connected to and responds to the movements of the control member while the other is directly connected to the gun. These motors and valves are located closely adjacent to the gun, while the connections between the follow-up levers and the control member enable remote location of the control member. As herein illustrated, these connections are made by means of Bowden wires which are flexible enough to be carried around any necessary corners and are stiff enough to transmit the force needed to operate the valves.

Preferably, a sighting device is provided which is also located remotely from the gun and which is mechanically connected to the gun to follow its movements. In a modified form of the invention, the control handle is directly attached to the sighting device. When this device is moved into visual alignment with the target, the gun is power-operated to bring it immediately into a corresponding alignment.

These and other features of the invention will best be understood from a consideration of the following description taken in connection with the accompanying drawings, in which

Fig. 1 is a vertical section taken longitudinally of the end of a fuselage, showing in side ele-

vation the gun mount, one of the control handles, and the sight;

Fig. 2 is a plan view on a larger scale of the control handles;

Fig. 3 is a detail in elevation, with parts broken away, of the handle-supporting bracket viewed from the side opposite to that shown in Fig. 1;

Fig. 4 is an elevation of the gun mounts looking toward the rear of the guns and with the guns themselves shown diagrammatically as if in section;

Fig. 5 is a horizontal section on broken line V—V of Fig. 4;

Fig. 6 is a vertical section through the gun-elevating motor taken on the line VI—VI of Fig. 4;

Fig. 7 is a plan view of the gun supports, showing the motor for swinging the guns laterally and illustrating a portion of the links connecting the gun to the sight;

Fig. 8 is a detail view of a portion of the connection between the linkage and the sight support and taken below a partition in the fuselage shown in Fig. 1;

Fig. 9 is a horizontal section on the line IX—IX of Fig. 4 and looking down upon the control valves;

Fig. 10 is an enlarged vertical section through the control valve shown at the right of Fig. 9;

Fig. 11 is an elevation of the support for the sight and is taken from the left in Fig. 1;

Fig. 12 is a view similar to Fig. 1 but showing an alternative arrangement in which the control handles are positioned near the sight;

Fig. 13 is an elevation showing the modified gun sight and control handles and taken from the left in Fig. 12;

Fig. 14 is a horizontal section on the line XIV—XIV of Fig. 13; and

Fig. 15 is a detail horizontal section on the line XV—XV of Fig. 12.

One opportunity for the utilization of the control apparatus to be described is found in airplanes where, for example, a gun compartment 10 is formed inside a section of the fuselage 12 as, for example, at the tail of an airplane where the twin guns 14 and 16, shown here in outline as being of the machine-gun type, are carried between partition plates 18 and 20 with the guns pointed rearwardly through a port 22 in any direction within a sixty-degree cone for each gun. Inasmuch as the skin of the fuselage provides no substantial protection against gun fire, an operator's compartment has been divided off by a partition 24 of armor plate in which, for convenience, there is a hinged door 26 to be utilized in supplying ammunition to the gun or for any necessary repair work. The head of the gunner will be within a bulge 28 of the fuselage which is provided with suitable windows 30 and, in this portion of the fuselage, there is provided a gun sight 32 of any suitable type but herein shown in outline as a standard reflex sight having a casing 34 and an aiming device utilizing a cross-hair image 36 (Fig. 11). The pointing of the gun is effected by means of dual control handles 38 universally supported upon a bracket 40 which is fastened to the under side of the armor partition 24.

The guns 14 and 16 are each provided with side rods 42 upon which there are clamped arms 44 (see also Figs. 4 and 7) which extend forwardly to provide fulcrums 46 and rearwardly to provide pivots 48. The fulcrums 46 which

permit the guns to swing about a horizontal axis are joined to suitable projections 50 upon pairs of vertical side plates 52. The side plates 52 are bent outwardly (Fig. 4) for compactness of design and the lower ends of each pair of the plates are bolted to a W-shaped member 54, shown at the right in Fig. 5. At their upper ends, the plates 52 are bolted to T-shaped caps 56 and 57, shown in elevation at the top of Fig. 4 and in plan in Fig. 7. The head portion of the T-shaped member 56 has a stud 58 (Fig. 7) in a ball-bearing about an axis normal to a cross plate 60 which is carried on the under side of the partition 18 shown in Fig. 1. A rod 216 attached to the cap 57 is similarly pivoted in plate 60. At the lower ends of these gun-carrying plates 52, the W-shaped pieces 54 (Fig. 4) are pinned to upright rods 62, aligned with stud 58 and rod 216, respectively. The lower end of each of these rods 62 is carried by ball bearings on a base plate 64 which is secured to the partition 20 of the fuselage. The T-shaped caps 56 and 57 at the top of the gun supports are interconnected by a link 66 (Fig. 7) so that they maintain parallelism, and the swinging of the gun mounts in azimuth about each of their respective axes is effected by power through the action of fluid-pressure means herein illustrated as a hydraulic motor 70 in which there is a piston 72 having a piston rod 73 connected by a link 74, at the left, to the left T-shaped member 55.

Tilting of the guns in elevation about the horizontal fulcrums 46 is effected by another hydraulic motor 80 (Figs. 4, 5 and 6) secured to the base plate 64. The piston 82 of this motor is joined by a piston rod 84 to a slide 86 having side fins 88 and at its lower end 90 encircling the outside of the cylinder of the motor 80. The lower end 90 is grooved to receive side plates 92 and 94 (Fig. 5) between the opposite ends of which are split blocks 96 which rotatably receive the sleeve-like lower portions 98 of travelers 100 each slidable upon one of the rods 62 and prevented from rotation with respect thereto by a spline 102. The travelers 100 are joined by links 104 to the pivots 48 upon the arms 44 which are clamped to the rods 42 at the sides of the guns. Operation of the motor 80 is therefore effective to tilt the guns about their horizontal fulcrums 46 so as to elevate or depress the muzzles without interfering with their lateral movement. It will be seen, therefore, that, since the lateral movements in a horizontal plane, for example, are independent of the up-and-down movements of the guns in vertical planes normal to the plane of its lateral movement, it is only necessary to control the admission of fluid to the motors 70 and 80 in order to be able to point the guns in any one of an infinite number of directions. In so doing, it is convenient to consider the movement of a point on the back end of the gun, for example, and to note that the angular movement of a point on the control handle is duplicated by the point on the gun, while the speed and extent of movement of the gun corresponds in a predetermined ratio, to the speed and extent of movement of the handle.

The pointing of the guns was formerly effected by grasping handles 110 fastened directly to the guns themselves to move them manually but, when the guns are mounted as they are upon airplanes, the air currents along the fuselage tend constantly to divert the guns from their intended directions, and the physical labor of moving and aiming them is very considerable.

Advantageously, therefore, the control handles 38 are mounted for movement on the bracket 40 so as to correspond to the movements of the handles 110 on the guns themselves. To this end, the handles are clamped to a T-shaped carrier 112 (Figs. 2 and 3) which is pivotally mounted at 114 between arms 116 extended upwardly from a rotor 118 having a depending sleeve portion pivoted in the bracket 40 for movement around a vertical axis. The handle carrier 112 is provided with a notched portion 120 which cooperates with a stop pin 122 to keep up and down movements of the guns within the cones of fire. Similarly, the rotor 118 has a notched portion 124 (Fig. 2) corresponding with a stop pin 126 similarly to limit lateral swinging of the handles and hence of the guns. On the carrier 112 is an arm 128 joined to a vertical rod 130 the lower end of which is connected to a bell crank 132 (Fig. 1) pivoted on the bracket 40. The other arm of the bell crank is joined to a Bowden wire 134 leading to a bell crank 136 pivoted upon the casing of a control-valve mechanism 140 supported on a bracket 141 attached to the base plate 64. This valve mechanism 140 controls the motor 80 by which elevational movements of the guns are produced. The rotor 118 associated with the control handle has an arm 142 (Fig. 2) to which there is joined a Bowden wire 144 leading through a guide 146 on the bracket 40 and another guide 148 (Fig. 9) to a bell crank 149 pivotally connected to the casing of a control-valve mechanism 150. The valve mechanism 150 is attached to the base plate 64 (Figs. 4 and 9) and controls movements of the guns in azimuth.

The control-valve mechanisms are identical in construction and operation and accordingly only one of them is herein illustrated and described in detail. To facilitate this description, a few parts of the valve mechanism 140, which parts are better shown and are like the corresponding parts of the valve mechanism 150, have been given numerals like those used in describing parts of the mechanism 150 but with a prime added to each number. Examples of such parts are the piston 165' and a block 168' notched at 178' to surround a fixed rod 180' and having pins 169' by which it is pivotally mounted in a forked follow-up lever 172'. This lever 172' is pivoted at one end to a link 174' joined by a pin 175 to the fins 88 of the slide moved by the motor 80 to produce movements of the guns in elevation. The balanced valve mechanism 150 by means of which the right and left movements of the gun to change its azimuth may be effected is shown in Figs. 9 and 10. The casing is provided with a port 152 which communicates by means of a pipe 154 with the left-hand end (Figs. 4 and 7) of the cylinder of the motor 70 so that, upon the admission of fluid through this pipe to the cylinder, the piston 72 shown in Fig. 7, will be moved to the right and the rear ends of the guns 14 and 16 at the lower end of Fig. 7 will be moved to the right. By means of another port 156 and a connecting pipe 158 joined to the right-hand end of the motor 70, movement of the rear ends of the guns to the left may be effected by the action of the pressure fluid on the opposite end of the piston 72. It will be recalled that the piston 72 is connected by a link 74 with the elongated portion of the T-shaped member 56 at the top of the gun carrier and that the two guns are connected by a parallel linkage including a link 66 (Fig. 7) so that they are always parallel.

In the casing of the valve 150 is a fixed sleeve 160 provided with external annular grooves connected by a series of openings, such as that shown at 162, to the interior of the valve in which there is a slide valve member 164 having a stem 165 and provided at each end with a flexible packing 166 such as is shown in section at the right end and having at its left end a guide block 168 which is similar in shape to the block 168' (shown at the left of Fig. 9) and has pivot pins 169 like the pins 169' in Fig. 9. These pins 169 are received in holes, slightly larger than the pins, in the side arms 170 of a forked lever 172 which acts as a control member and is joined at its lower end by a link 174 to an arm 176 clamped to one of the vertical rods 62 which turns in its ball-bearing base whenever the guns are swung laterally. In that block 168 is a notch (not shown), such as that shown at 178' at the left of Fig. 9, in the block 168'. The notch of the block 168 surrounds a fixed rod 180 extending out from the valve casing and having limit nuts 182 to control its range of movement. The other end of the lever 172 is connected by a link 184 to an end of the bell crank 149 to which there are transmitted the right-and-left movements of the handles 38 through the Bowden wire 144. The valve member 164 has a series of piston-like enlargements or lands 167 so that fluid under pressure delivered to the valve casing through a port 190 will be transmitted to either the right or the left end of the cylinder of the motor 70 as the handles 38 are moved. The enlargements 167 are of equal diameter so that the valve is balanced and the widths of the lands are almost exactly equal to the diameters of the coacting openings, such as that at 162. Hence, only a minute movement of the valve member 164 is needed to open the valve, thus making the apparatus instantly responsive to movements of the control handles 38. The annular grooves in the valve sleeve 160 adjacent to the ends thereof are interconnected by a longitudinal passage 194 so that the oil, in that end of the cylinder 70 toward which the piston 72 is moving, can be exhausted through a port 192, regardless of which way the piston 72 is moved.

There is provided, therefore, by the control member 172 which is arranged to operate the valve 150 and which is oppositely connected to the work and to the operator control, a follow-up mechanism the action of which is automatic. The action of this follow-up mechanism moreover is continuous in that it effects an instant response to the movements of the control handle thereby avoiding any lag or hunting movements of the gun and insuring the duplication by the gun of the position of the control handle.

A movement of the gun is immediately transmitted to the sight 32 by reason of mechanical connections extending between the two. To this end, the sight is attached to hangers 200 (Fig. 11) pivoted at 202 between the upstanding arms of a stirrup-like support 204, which is riveted upon the upper end of a vertical rod 206. The lower end of this rod is rotatably supported in a bearing 208 (Figs. 1 and 8) secured to the partition 24, and turning movement about a vertical axis, to accord with the lateral deflection in azimuth of the gun, is imparted to this rod by means of a lever 210 (Figs. 7 and 8) attached thereto and joined by a connecting rod 212 to a lever 214 secured to the top of the vertical rod 216, which is fastened to the cap 57 at the top 75 of one of the gun supports (Fig. 4).

Furthermore, it is necessary to tilt the sight 32 about the pivots 202 to a degree matching the up-and-down tilting of the guns, and this is done by means of a lever 220 (Fig. 1) fulcrumed at 222 on the inner side of the fuselage 12. The lever 220 has its outer end 224 forked (Figs. 4 and 7) and slidably in the grooves of a block 226 mounted on the upper end of a rod 228. This rod 228 slides in a suitable bearing in the upper plate 60 of the gun carrier and is given a reduced movement proportionate to the movement of the gun-elevating slide 86 by means of a lever 230 fulcrumed at one end upon brackets 232 (Figs. 1 and 4) depending from the plate 60, and pivoted at the other end to a connecting rod 234 which extends down to and is fastened to the slide 86. At its inner end, the lever 220 is forked at 236 (Fig. 7) and has a sliding and pivotal connection 238 (Fig. 11) with a block member 240 which is slidably mounted on the supporting rod 206 and has a spool portion 242 receiving a notched yoke 244 (see also Fig. 7). The ends of this yoke are joined by flat links 246 (Fig. 1) to rigid arms 248 which are integral with the hangers 200. The lower ends of these links 246 are connected by parallel links 250 to downwardly directed arms 252 which are a part of the stirrup-like hanger or support 204 (Fig. 11). The hanger or support 204 thus forms a part of a parallel linkage, including the links 246, the arms 248 and the links 250. Up-and-down movements of the gun-tilting slide 86 are therefore communicated through the reducing lever 230 to the long lever 220 and thence to the parallel linkage which is joined to the yoke 244. The mechanism just described is, therefore, capable of turning and tilting the sight 32 so that it is always parallel to the longitudinal axes of the guns 14 and 16 and gives the gunner an accurate indication of the direction in which they are pointed.

In a modified form of the invention illustrated in Figs. 12 to 15, inclusive, the mechanism for turning and tilting the gun is exactly the same as in the arrangement already described, but the control handles 260 are here mounted on arms 262 integral with hangers 264 for the gun sight 32. These hangers also have forwardly extending arms 266 for a purpose similar to that of the rigid arms 243. The hangers 264 are pivotally mounted at 268 at the upper ends of the arms of a supporting stirrup 270 which is fastened to the top of a vertical rod 272 and the latter is rotatable in a bearing 274 attached to the underside of the partition 24, and has at its lower end an arm 276 (Fig. 15) joined by a link 278 to a lever 280 which is pivoted upon the lower end of a bracket 282 attached to the partition 24. At the other end of the lever 280, there is attached a Bowden wire 284 leading to the valve 150 which controls the lateral swinging movements of the guns as the gun supports are turned by means of the power transmitted from the motor 70. An extension 286 of the bracket 282 provides a support for the sheath 288 of the Bowden wire 284. The stirrup 270 is provided with depending arms 290 joined by parallel links 292 to upright links 294, the lower ends of which are bolted to a yoke 296 (Fig. 14) engaging the groove of a spool 298 (Figs. 12 and 13) slidably vertically on the rod 272. This spool is connected by links 300 to a forked lever 302 (Figs. 11 and 15), the other end of which is pivoted on the bracket 282. This forked lever 302 has a nub 304 to which is connected the upper end of a Bowden wire 306, which controls the valve 140 that determines

the up-and-down movements of the slide 86 for tilting the guns to elevate or depress them. An arm 308 supports a sheath 310 for this Bowden wire. It will be noted that the yoke 296 (Fig. 14) is provided with a stop pin 312, which is adapted to be engaged by ears on a collar 314 secured to the upright sight-supporting rod 272. By this arrangement, the lateral turning of the sight and the handles 260 is limited to the range of movement, laterally, of the guns and supports. It follows that this modified mechanism brings the control handles 260 to a point beside the sight 32, and, by reason of the direct connection between the handles and the sight, causes substantially synchronous movements of the latter and the guns, as the Bowden wires 284 and 306, by reason of their connections to the control valves 150 and 140, produce corresponding movements of the guns.

In the operation of the arrangement illustrated in Figs. 1 to 11, the gunner, grasping the control handles 38, will move them about the universal mounting provided on the bracket 40 and, by means of the control mechanism including the directly-connected follow-ups, will cause an immediate training of the guns in such a manner that the angular displacement of a point upon the rear end of a gun will correspond exactly to the movements of a point on the control handle.

These movements will be compounded of vertical movements in planes normal to one another about the fulcrums 46 and of lateral swinging movements about the axis of a rod 62. The actual movement of a point on the rear end of the gun will therefore take place along any one of a plurality of paths in either direction. Since these movements are compounded of movements produced in azimuth and movements produced in elevation, it will be sufficient to note the operation of either one of these devices. For example, if the control handle 38 is swung about its vertical axis, its movement will be transmitted through the Bowden wire 144 (Figs. 2 and 9) to the bell crank 149 which is directly connected by the link 184 to one end of the follow-up mechanism exemplified by the lever 172. This movement of one end of the lever 172 produced by the handle will be immediately transmitted to the valve 150 as the lever swings about the fulcrum provided by the link 174, and the movement transmitted to the valve will cause the flow of fluid under pressure to that end of the fluid motor 70 (Fig. 7) which will cause a swinging movement in a horizontal plane, and in a direction corresponding to that of the handle movement, of the guns 14 and 16 about their vertical pivots 58 and 62 (Fig. 4). If the handle, as viewed in Fig. 2, is moved to the left, for example, the Bowden wire 144 will be pushed, causing the upper end of the lever 172, as viewed in plan in Fig. 9, to be moved to the right. This will shift the valve member 164 to the right, in Fig. 10, letting fluid under pressure flow through the port 190 and thence through the connecting pipe 158 to the right end of the motor 70, thus causing the rear ends of the guns to be swung to the left.

The speed of this movement will depend upon the degree of opening of the passage 156 by the valve member 164 and this will depend upon the speed of movement of the control handle 38. Thus a quick movement of the handle will be accompanied by a quick operation of the motor 70, and it will be noted that this action takes place by reason of a direct connection of the

control handle 33 to the valve member. Just as soon as the motor starts to move, thereby turning the guns, there will be a turning movement of the arm 176 (Fig. 9) clockwise in this particular instance, thereby reacting directly through the link 174 upon the follow-up lever 172 and tending to swing this lever about its pivotal connection to the link 184 in a direction to draw the valve member 164 to the left so as again to shut off the supply of pressure fluid through the pipe 158 to the motor unless the operator is at the same time moving the hand lever 38 to the left to counteract this tendency to close the valve 164. In consequence of this arrangement, the operator is under no burden of returning the control handle to any initial position but moves it only where he would move it if he were operating the guns manually. The extent of movement of the guns accordingly corresponds, either exactly or in a predetermined ratio, to the movement of the control handle 38. The extent of the angular movement of the gun is the same as the extent of angular movement of the control handle. It has already been noted that the speed and direction of movement of the gun depend upon the speed and direction of movement of the control handle and, consequently, the direction, speed and extent of movement of the device are determined and controlled directly and continuously by the direction, speed and extent of movement of the control member, and, even though the control member 38 is remotely positioned from the device, here the guns, the gunner can with confidence initiate the firing of the guns at any time with the assurance that there is no lag or hunting and that the guns occupy a position like that occupied by the control member. It will be observed that the sighting device 32 will be immediately and correspondingly moved to bring it into visual alignment with the target. By reason of the direct connections of the follow-up to the control handle and to the gun, the extent of movement of the gun and the speed of movement thereof will correspond in a predetermined ratio determined by the design of the follow-up lever to the speed and extent of movement of the control handle.

In the device illustrated in Figs. 12 to 15, inclusive, where the control handles are directly connected to the sighting device, any theoretical lag between the movements of the gun and the movements of the handle, so that the bringing of the sighting device into visual alignment with the target will slightly anticipate the movements of the gun, is so slight as to be substantially imperceptible to the operator.

Having thus described our invention, what we claim as new and desire to secure by Letters Patent of the United States is:

1. In a power operated mount for a gun, a pair of normally-vertical side plates embracing said gun and interconnected above and below said gun to form a frame, means pivoting said gun on and between said plates for elevation about a first normally-horizontal axis fixed relatively thereto, means mounting said frame for pivotal movement about a second normally-vertical axis and including a shaft aligned with said second axis and fixed to said frame, a traveler guided for translation only on and along said shaft, motor means connected to so translate said traveler,

and link means pivoted at one end of said gun on an axis parallel to and offset with respect to said first axis, and to said traveler at the other end, whereby operation of said power means pivots said gun in elevation.

- 5 2. In a power-operated mount for a gun, a pair of vertical side plates connected to form a frame embracing said gun, means pivoting said gun on and within said frame for elevation about a normally-horizontal first axis, means pivoting said frame for movement about a normally-vertical second axis and including a splined shaft aligned with said second axis and rigid with said frame, a traveler surrounding said shaft and engaging the spline thereof for translation only on and along said shaft, a link pivoted to said traveler at one end and to said gun at the other end, upon an axis parallel to and offset from said first axis, a hydraulic motor comprising a cylinder, a piston and piston rod, having their axis parallel to and offset from said second axis, a guide mounted for translation on and along said cylinder, a rigid connection between said piston rod and guide, an arm fixed to said guide and extending adjacent said traveler, and a swivel connection between said arm and traveler, whereby reciprocation of said piston, rod, guide, arm and traveler, pivotally moves the gun in elevation.
- 10 3. The structure as in claim 2, said frame including a cap at the top thereof, a second hydraulic motor comprising a cylinder, piston and piston rod, adjacent said cap and having its axis normal to said second axis, and a link pivoted to said rod and to said cap, at a point off-set from said second axis.
- 15 4. In a power-operated mount for twin guns mounted side by side and adapted for training and elevation in synchronism, a pair of frames, each surrounding a respective gun, means mounting each gun in its frame for elevation with respect thereto about a normally-horizontal first axis, means mounting each frame for movement about a normally-vertical second axis and including a pair of parallel shafts each co-axial with a respective second axis, a pair of travelers each mounted for translation only on and along a respective shaft, link means connecting each traveler with a respective gun, on pivot axes parallel to and offset from said first axis, a first motor between and parallel with said shafts and including a cylinder, piston and piston rod, a guide mounted for translation on and along said cylinder and rigidly connected with said piston rod, and a member fixed to said guide and having oppositely projecting arms each swiveled to a respective one of said travelers, whereby on application of hydraulic pressure to said piston, said rod, member and travelers are reciprocated as a unit, to synchronously move said guns in elevation.
- 20 5. The structure as in claim 4, a link pivoted to said frames and connecting the same for movement in unison about said second axis, a second motor comprising a cylinder, piston and piston rod, with their axis normally horizontal, and a direct connection between said last-named piston rod and one of said frames, whereby operation of said second motor rotates said guns in unison about said second axis.
- 25 60 6. The structure as in claim 4, a link pivoted to said frames and connecting the same for movement in unison about said second axis, a second motor comprising a cylinder, piston and piston rod, with their axis normally horizontal, and a direct connection between said last-named piston rod and one of said frames, whereby operation of said second motor rotates said guns in unison about said second axis.
